COOLING JACKET FOR COMBUSTION CHAMBERS

Geoffrey Joseph Gollin, Great Saint Helens, London, England, assignor to The Asiatic Petroleum Company, Limited, London, England

Application September 23, 1943, Serial No. 503,521
In Great Britain December 7, 1942

1 Claim. (Cl. 60—46)

1

The use of a liquid coolant such as water, passing through an external passage or jacket around a combustion chamber or engine cylinder is well known. The rate at which heat is picked up by the fluid from the hot surface with which it is brought into contact is known to be a function of the velocity of flow of the fluid relative to that surface. In certain cases the amount of heat which it is desired to remove from the surface is of such a high order that when using an ordinary type of cooling jacket in order to attain a sufficiently high fluid velocity and therefore rate of heat transfer it is necessary either to employ an inordinate amount of fluid or fluid passages having an extraordinary small cross section.

The cooling jacket according to the present invention is designed so that the coolant would pass over the surface or surfaces to be cooled at a far higher speed than that equivalent to the quantity of coolant passing through the jacket and the cross sectional area offered to the flow. Its characteristic feature is that it has an annular passage and an inlet adapted for the admission of coolant at high velocity so as to rotate the body of coolant in the passage at high speed, the cross-sectional area of the annular passage being large in relation to the area of flow from the inlet.

The annular passage may have various forms in cross section according to the purpose and application of its use.

In one form it is substantially triangular in cross-section, the inlet being arranged tangentially at a point corresponding to an apex of the triangle. With this form the cooling surface may be substantially of conical form with the inlet at the apex of the triangular cross-section corresponding to the wider part of the cone.

A restricted outlet for the coolant may be provided and this in the case of the conical form of the cooling surface may be at or near the narrow part of the cone. The outlet may comprise a plurality of orifices in and spaced around a wall of the jacket. In this case the coolant may be discharged into the space to be cooled, e. g. into a combustion chamber around part of which the cooling jacket is arranged.

In cases where the operation of the furnace or engine is of short duration it is possible, according to the invention, to make the capacity of the jacket such that the coolant present in the jacket has a sufficient heat capacity to absorb heat desired to be taken away from the cooling surface during the time of operation, in which case the fluid passed in and out of the jacket is

2

just adequate to maintain the fluid in the jacket in a state of high rotational velocity.

By causing the incoming coolant to enter at a high velocity, e. g. through the constriction in the inlet pipe, a very small quantity of coolant will suffice to maintain the body of coolant in the annular jacket at a high rotational velocity. For instance, in a particular case water may be introduced at a velocity of, say, 100 feet per second, 10 using about two pounds of water per second, so that the momentum of the incoming jet keeps the water in the jacket rotating at a speed of, say, 30 feet per second. If such an amount of water were passed into the annulus through an inlet 15 of substantially the same size in cross-section as that of the annulus the velocity of rotation of the water in the annulus, the conditions otherwise being the same, would be only about 2½ feet per second. Accordingly by the invention it is 20 rendered possible to remove heat from the surface exposed to the radiation in a combustion chamber or to other form of heat at a far greater rate than would otherwise be feasible. If the same high speed were to be maintained with an ordinary jacket, using the same quantity of water, 25 the cooling passage would have to be reduced to a width of about one-sixteenth of an inch. Passages as small as this would be difficult to make and it could not be guaranteed that there would 30 be even flow and cooling over the whole surface.

A further advantage of the cooling jacket according to the invention is that the relatively large section annulus is readily cleaned and that there is a substantially equal cooling effect over 35 different parts of the cooling surface.

The invention is illustrated by way of example in the accompanying drawings, in which Figure 1 shows in sectional elevation, partly broken away, the head of a combustion chamber provided with the cooling jacket of the present invention, whilst 40 Figure 2 is a plan view of the structure of Figure 1, partly sectional on the line 2—2 in the latter figure.

Referring to the drawings, 1 indicates the head 45 of the shell of a combustion chamber and 2 indicates a refractory lining within the combustion chamber shell.

To the shell 1 is fixed heat-producing means constituted by a fuel burner and its associated inlet ducts. The burner comprises a central spray nozzle 3 into which liquid fuel is fed tangentially at 4 to produce a vortex. The fuel inlet to the nozzle is from a duct 5 and the outlet into the combustion chamber is through the opening 6.

55 Surrounding the nozzle 3 is an outer member 7

which leaves an annular passage 8 for the introduction of liquid oxidant between the member 7 and the nozzle 3.

Fitted within the combustion chamber and surrounding the space in front of the nozzle is an annular cooling jacket 9 which is of substantially triangular cross-section, the wall 10 of which exposes to the combustion space a cooling surface in the shape of a frustum of a cone.

In the angle formed between the inner and outer walls 10 and 11 of the cooling jacket, i. e. behind the wider part of the cone of the cooling surface 10, is a tangential inlet 12 for introducing a coolant into the cooling jacket, which inlet is provided with a constriction 13. Two rings of orifices 14 in the inner wall of the cooling jacket close to the nozzle 3 provide an outlet for the coolant into the combustion space.

It will be appreciated that with a cooling jacket of this construction the coolant may be admitted at high velocity through the tangential constricted inlet so that the body of coolant in the annular jacket is rotated at high speed, whilst the amount of coolant admitted, and discharged, is small, having regard to the cooling effect which the coolant exercises across the cooling surface 10 by reason of its rapid sweeping over the inside of that surface.

I claim:

In combination with heat-producing means, a cooling jacket arranged to expose a rapidly cooled

wall surface of which at least a part is substantially in the form of a frustum of a cone surrounding a zone in the vicinity of said heat-producing means, the said cooling jacket having an inlet tangentially disposed adjacent the part of the conical surface of greatest radius for admitting a cooling liquid at high velocity into said annular passage and having a cross-sectional area small in relation to the cross-sectional area of said annular passage, and at least one outlet from the part of the cooling jacket nearest to the heat-producing means for discharging the cooling liquid into said zone.

GEOFFREY JOSEPH GOLLIN.
